UNITED STATES PATENT OFFICE.

EDWIN D. WASSELL, OF PITTSBURG, PENNSYLVANIA, ASSIGNOR TO ANN ISABELL WASSELL.

METALLIC VEHICLE-WHEEL.

SPECIFICATION forming part of Letters Patent No. 625,000, dated May 16, 1899.

Application filed August 26, 1898. Serial No. 689,554. (No model.)

To all whom it may concern:

Be it known that I, EDWIN D. WASSELL, a citizen of the United States, residing at Pittsburgh, in the county of Allegheny and State of Pennsylvania, have invented certain new and useful Improvements in Metallic Vehicle-Wheels; and I do hereby declare the following to be a full, clear, and exact description of the invention, such as will enable others skilled in the art to which it appertains to make and use the same.

My present invention relates to metallic vehicle-wheels; and has for its object certain improvements in construction whereby a compact and durable wheel is produced at the minimum cost, as will be fully disclosed in the following specification and claims.

In the accompanying drawings, which form part of this specification, Figure 1 represents a vertical longitudinal section of my improved wheel; Fig. 2, a vertical transverse section on the line $x-x$, Fig. 1, looking in the direction of the arrow; Fig. 3, a side elevation of the axle-box detached; Fig. 4, a side elevation, partly in section, of part of a spoke, showing a modification of the construction; Fig. 5, a vertical longitudinal section of one of the felly spoke-boxes, and Fig. 6 a vertical transverse section of the same.

Reference being had to the drawings and the letters thereon, A indicates the hub of the wheel, which is made of two metallic sections a and b , the former having an internally-screw-threaded extension c and a shoulder d and the latter an externally-screw-threaded extension e and a shoulder f . The sections are cored out at g to reduce their weight and are secured together by the screw-threaded extensions c and e . Within the sections a and b of the hub and extending beyond the outer end of each is a sleeve i , each having an outwardly-projecting flange l at its inner end, by which the sleeves are secured in the sections a and b and are engaged by the shoulder d of the section a and the inner end m of the section b , with gaskets n , of rubber or soft metal, between the flanges, as shown in Fig. 1 of the drawings.

Within the sleeves i are cast-iron pieces o , each having concentric flanges or ribs q , between which are rabbets or spaces r to re-

duce their weight, while the ribs form supports for the sleeves, and between the inner ends of the pieces o are filling-pieces s , preferably of soft metal—such as lead, Babbitt 55 metal, or other composition—to deaden the ringing sound produced by the vibrations of the spokes. The pieces s are in the form of rings and fill the longitudinal grooves in the axle-box B , which will be hereinafter more 60 fully described, and the gasket n extends into said axle-box and between the inner ends of the pieces s .

The axle-box B is of a diameter to fit the bore of the filling-pieces o , is provided with 65 a collar t at its inner end, against which the outer end of the filling-piece p bears, and with longitudinal grooves u , in which the inner ends of the spokes of the wheel rest, so that the thrust of the spokes in the grooves 70 prevent the axle-box turning in the hub, in which function they are assisted by the pieces s , extending into and filling said grooves.

The spokes C extend through the thickest portion of the sections a and b of the hub, as 75 shown in Fig. 1, and by which it will be seen that the inner spokes pass through the screw-joint of the said sections by passing through the extensions c and e , and the possibility of the sections separating is thereby prevented. 80 The spokes also pass through the filling-pieces s and with their rounded heads v or inner ends of the spokes rest in the grooves u of the axle-box B . The spokes are tubular and for light vehicles are provided with short 85 solid steel rods w , which extend beyond the hub and upon which the heads y are formed, and upon the shoulder of which head the inner end of the tubular spoke rests. These rods serve to stiffen the spokes at the point 90 subject to the greatest strain and prevent the spokes being bent at the hub, as frequently occurs in this class of wheels. For heavy vehicles the spokes D (shown in Fig. 4) may be used. In this construction the spoke is reinforced by an outer tube z , which enters the hub and is provided with a rounded end, z , to engage the groove in the axle-box. 95

The outer end of the spoke is corrugated, as at a' , and is secured in the felly by means 100 of a box b' , which I designate the "felly spoke-box," in which the spoke is embedded in soft

- metal or rubber, as shown in Fig. 1. The felly spoke-box is provided with a bar or seat *c*', having a concave outer surface *d*' to receive the convex inner surface *e*' of the tire 5 *F*, a boss *F*' on the inner side of the bar *c*' to enter the end of the tubular spoke, and with flanges *g*' *g*' to confine the soft metal or rubber in which the spokes are embedded.
- The tire *F* is provided with inwardly-projecting flanges *h*' *h*', which engage the sides 10 of the felly *E*, which flanges, with the concavo-convex joint between felly spoke-box and the tire, serve to prevent the tire slipping off the felly.
- 15 It will be observed that the grooves *u* in the axle-box extend from the shoulder *i*' to the outer end of the box to enable the box to be removed when worn out.
- The axle *G* extends through the axle-box 20 and is provided with a washer *k*' and a nut *l*' at the outer end and a shoulder *m*' at the inner end of its spindle *n*', by which the composite parts of the hub are secured against longitudinal displacement.
- 25 In assembling the parts of the hub the filling-pieces *o* *p* and *s* *s* and the sleeves *i* *k* are inserted from the inner ends of the sections *a* *b* and forced into position by pressure, when the gasket *n* is inserted and the sections *a* *b* 30 are secured together. The holes for the spokes are then drilled in the hub and the hub finished, after which the spokes are inserted in the hub, the felly applied, and the tire shrunk on the felly in the usual manner.
- 35 Having thus fully described my invention, what I claim is—
1. In a metallic vehicle-wheel, tubular spokes reinforced at their inner ends by metallic rods having heads at their inner ends 40 and extending beyond the hub of the wheel, in combination with an axle-box provided with grooves engaged by said reinforces.
  2. In a metallic vehicle-wheel, tubular reinforced spokes, the reinforce having rounded inner ends and extending beyond the hub 45 of the wheel, in combination with a grooved axle-box and filling-pieces, said spokes engaging the filling-pieces and the grooves in the axle-box.
  3. In a metallic vehicle-wheel, tubular spokes reinforced at their inner ends, the reinforce extending beyond the hub of the wheel and provided with rounded inner ends, 50 in combination with a grooved axle-box engaged by the spokes.

4. In a metallic vehicle-wheel, a hub in two sections having overlapping screw-threaded extensions, and an axle-box provided with longitudinal grooves, in combination with spokes extending through said extensions and 60 engaging the grooves in the axle-box.

5. In a metallic vehicle-wheel, a hub in two connected sections, in combination with sleeves within said sections and extending beyond each section and having flanges at 65 their inner ends which are engaged by the sections.

6. In a metallic vehicle-wheel, a hub in two connected sections, in combination with sleeves within and extending from each section and having flanges at their inner ends which are engaged by the sections, and a gasket between the outer surface of the flanges. 70

7. In a metallic vehicle-wheel a sectional hub in combination with a grooved axle-box, 75 filling-pieces engaging the grooves in the axle-box, and spokes engaging said filling-pieces and the grooves in the axle-box.

8. In a metallic vehicle-wheel, a hub consisting of two connected sections, sleeves within 80 said sections and extending beyond the ends thereof, and filling-pieces having concentric flanges or ribs to support said sleeve, and filling-pieces through which the inner ends of the spokes extend. 85

9. In a metallic vehicle-wheel, tubular spokes having rounded inner ends, in combination with a hub, and an axle-box having seats to receive the rounded ends of the spokes, and filling-pieces engaged by the spokes. 90

10. In a metallic vehicle-wheel, a felly spoke-box having a bar provided with inwardly-projecting flanges, a filling inclosed by the flanges, and a boss to engage the end of the spoke.

11. In a metallic vehicle-wheel a felly spoke-box having a bar provided with a concave outer surface, inwardly-projecting flanges, a filling inclosed by the flanges, and a boss to engage the end of the spoke. 95

12. In a metallic vehicle-wheel, a felly spoke-box having a bar provided with a concave outer surface, in combination with a tire provided with a convex surface on its inner side and with inwardly-extending flanges. 100

In testimony whereof I affix my signature 105 in presence of two witnesses.

EDWIN D. WASSELL.
